DISPLAY SIGN

George H. Evans, Washington, D. C., assignor of
one-half to Richard K. Stevens, Washington,
D. C.

Application October 21, 1938, Serial No. 236,349

33 Claims. (Cl. 40—133)

This invention relates to display signs, and more particularly to such signs in which sufficient movement is imparted to elements thereof to attract the attention of persons in proximity thereto while the characters displayed by the sign are sufficiently stationary to readily convey to an observer the intended significance.

The desirability of utilizing signs including means to attract the attention of the public thereunto is so universally recognized that it is now common practice to produce extremely large and expensive electrical signs having novel illuminating sequence or other means for attracting and maintaining attention. These features are reiterated in smaller signs insofar as it is practicable from the standpoint of expense in the light of the scope of advertising effectiveness. The efficiency of signs in which the primary attention engaging media is mechanical, as distinguished from electrical, has been long recognized likewise, but, because of certain hitherto prevalent concomitant disadvantages, their practical use has been limited to a large extent.

It is an object of this invention to overcome the disadvantages formerly incident to the commercial use of mechanical signs. In addition, a sign comprising the present invention may be economical to construct, silent in operation, and may be inexpensively operated. Furthermore, a sign is contemplated that may be universally positioned with respect to light sources and will produce novel and attractive effects to create and maintain interest.

More specifically, this invention contemplates the provision of a display device in which an advertising design may be composed of a plurality of continuously or periodically movable display elements which present a scintillating or flowing effect, thereby attracting the attention of passers-by, while at the same time, the design or insignia itself may be maintained perfectly legible. In the production of such display devices, this invention contemplates the employment of a plurality of adjacent spindles so positioned with respect to a driving means that they may be frictionally engaged and rotated thereby.

Other objects and advantages of the invention will be apparent from the following detailed description of certain preferred embodiments thereof, reference being had to the annexed sheets of drawings wherein like reference characters indicate like parts throughout, and in which:

Fig. 1 is a front view in elevation of one embodiment of a display sign made in accordance with this invention;

Fig. 2 is a view in cross section taken along the line 2—2 of Fig. 1;

Fig. 3 is a front view in elevation of a modification of the invention showing slanted display members frictionally driven by a rotating shaft; 5

Fig. 4 is a view in cross section taken along the line 4—4 of Fig. 3;

Fig. 5 is a plan view of a modification of the invention wherein portions are cut away to show the display insignia rotatable by frictional engagement with a revolving disc; 10

Fig. 6 is a view in cross section taken along the line 6—6 of Fig. 5;

Fig. 7 is a view in perspective of a resilient mounting to facilitate frictional engagement with 15 a driving member;

Fig. 8 is a front view in elevation of a modification of the present invention, portions thereof being cut away to show the display members and driving means; 20

Fig. 9 is a view in perspective of a plain display element for use in signs made in accordance with this invention; and

Figs. 10 to 14 are perspective views of modified display elements for use in signs made in accordance with this invention. 25

Referring specifically to Figs. 1 and 2 of the drawings, a display unit may comprise a base 1 supporting a motor 2 which is connected by suitable gear reduction means 3 to a shaft 4 which carries a drum 5. Drum 5 frictionally drives a belt 7 carried by drums 5 and 3. The belt 7 is retained in position by an angle member 9 with a retaining shoulder 10 against which the outer and lower edge of the belt 7 may slide during its upper run. Display elements 12 are mounted on a plurality of spindles 13 or made integral therewith. 30

The spindles 13 may be positioned parallelly to one another and in the same vertical plane by elongated angle brackets 14 having bearings therein to support said spindles 13 near their upper and lower extremities. These spindles are provided with contacting rotors 15, the peripheries of which rest against the driving belt 7 whereby 35 to impart motion to the spindles 13. The display elements 12 may be of such material and configuration that light falling upon them may be reflected in various formations and directions as will be completely described hereinafter. Various attractive effects may be secured by locating the display elements 12 in front of a suitable background 16. 40

By reference to Fig. 2 it will be noted that the spindles 13 are positioned perpendicularly to the 45

base 1. The display is thereby maintained in the conventional upright position. Accordingly, the motor assembly 2, drums 5 and 8, support 9, and belt 7 are mounted at an angle with respect to 5 the base 1. This angular mounting permits the spindles 13 to be positioned in a vertical plane and at the same time provides contact between belt 7 and rotors 15 only at the outer peripheries thereof, whereby the rotors 15 are caused to rotate. Instead of the embodiment illustrated, 10 however, it is possible to arrange a display in which the spindles are mounted at almost any angle with respect to the belt, the only limitation being that the driving members be so positioned 15 with respect to the belt that they may be frictionally engaged and rotated thereby.

To these effects can also be added a successive transverse alternate cessation and resumption of motion which may be accomplished by the use of 20 a belt of varying width. If, for example, the belt 7 is cut away as shown at 17, the narrow remaining portion will by-pass the rotors 15 thereby permitting the same to rest on the stationary angle support 9. As the belt continues its journey, 25 motion will be resumed as successive driving rollers are again engaged by the widened portion 18 of the belt.

In Figs. 3 and 4, a modification of the driving means is shown which is applicable to a display 30 device where the spindles carrying display indicia are disposed at a slight inclination with respect to the driving means but lie in substantially the same vertical plane. Display elements 12 are fixed on spindles 13 which are mounted at an angle 35 in suitable bearings in brackets 20 supported by the background 16. A suitable source of power 2 mounted on a base 1 drives a shaft 21, journaled in a bearing 22. A drive cylinder 23 is mounted on shaft 21 or made integral therewith. This 40 cylinder 23 is arranged to frictionally engage the peripheries of discs 24 which are secured to the lower ends of spindles 13. This type of drive means is particularly advantageous as it comprises the minimum of parts and is substantially 45 wear-proof.

It has been found desirable, especially in signs where the display indicia in collocation represent various letters of the alphabet, to position both 50 of the guide bearings shown at 20 below the display indicia. This has the obvious advantage of facilitating a change in the length of any particular display member so that different words 55 may be spelled when the advertiser is desirous of changing the subject matter of the advertisement. Of course, to make this possible it may be necessary to have a suitable key arrangement 60 between the spindles 13 and the rotors 15 whereby the two may be readily disengaged and yet when in engagement the latter will positively drive the former.

A modification of the present invention especially suitable for displays other than those in which words, slogans, or phrases are spelled out, is shown in Figs. 5 and 6. In this modification 65 the display elements 12 are supported in a circular arrangement on a base 26 which is cylindrical in shape and hollow. These display elements 12 are of the same type as those used in the above modification and are supported by spindles 13 which have discs 24 secured to the lower ends 70 thereof. The spindles 13 are journaled in bearings carried by the top wall 27 of the base 26 and a circular cover 28 which is spaced from said base 26 on a centrally located column 29. Mounted within base 26 is a suitable source of 75

power 2 connected by a suitable gear mechanism 30 in any conventional manner to a shaft 31 which is concentrically mounted with respect to the base and is adapted to drive a frusto-conical disc 32. The assembly is arranged so that the 5 discs 24, carried by the spindles 13, rest against the sloping edges 33 of the driving disc 32. As in the foregoing modifications it will be seen that the rotors or driving discs 24 frictionally engage the frusto-conical disc 32 only at their 10 peripheries so that a frictional drive between the two will result in rotation of spindles 13 carrying the display elements 12.

A detailed modification of a means for maintaining the driving rotary frictional engagement 15 with a moving surface is shown in Fig. 7. Base 35 in Fig. 7 is provided with an upstanding flange 36 running for the entire length of the moving portions of the display. Resting against the inner edge of upstanding flange 36 are springs 37 20 which are positioned to resiliently urge free floating thrust bearings 38. The thrust of the springs 37 will act to move the bearing blocks 38 away from the flange 36 and toward the rear of the sign. Journaled within the block bearings 38 are 25 shafts 13 which carry the display elements 12. Near the lower journaled ends of the shafts 13, but just short thereof, are positioned contact rotors 39 which are cylindrical in shape. The peripheries of the contact rotors 39 are resiliently 30 urged into frictional engagement with a belt 40 which may be driven by a suitable source of power in a position vertical to the base 35. The belt 40 rests against and may be supported by an independently mounted stationary support member 41. It will be seen that the rotors 39 will be maintained in constant engagement with the belt 40 as a result of the action of the springs 37 on the thrust bearings 38, which bearings carry the spindles 13 and consequently the contact rotors 39.

Still another modification of my invention is shown in Fig. 8 wherein the display elements 12 are housed within transparent or translucent 45 housings which may be made of glass, suitable molding plastics, or other desirable materials. In addition, these housings may be provided with surfaces comprising prismatic, lenticular, or other formations so as to optically effect the light rays reflected from the display elements 12 as more 50 fully described in my application for patent Ser. No. 216,361. Likewise, this modification illustrates an additional detail which may be incorporated in my invention, namely, the inclusion of a built-in light source to provide illumination 55 for the display elements 12. Furthermore provision is made to filter this light so as to present vari-colored effects.

In this modification which is shown in Fig. 8, a fanciful display is made which somewhat combines the features of the disclosures of Figs. 3 and 5. The spindles 13 may be mounted in various angular positions and the contact rotors 24 may be mounted not only to contact the periphery 33 of the frusto-conical driving disc 32 but may also contact its upper surface 42. This modification may comprise a hollow base 43 wherein is mounted a motor 2, gear box 30, and shaft 31 supporting and driving the frusto-conical disc 32. The display elements 12 are supported on 70 spindles 13 which are mounted in suitable bearings 46 and 47 which bearings may be provided in the top and bottom walls of the housings 45.

In addition to the frusto-conical driving disc 32 there is mounted on the drive shaft 31 a glass 75

plate 48 which may be variedly colored so that light from an illuminating means 44 may be filtered upwardly into the translucent or transparent housings 45 containing the display elements 12. Instead of a multi-colored glass disc at 48, an ordinary colored disc with multi-colored filters may be employed. Although the housing members 45 are shown triangular, they may be variously altered in configuration to harmonize with any particular display in contemplation. The spindles may be sloped either inwardly or outwardly with respect to the particular device shown, and they may be made of varying materials particularly suitable for the intended purpose. It is also contemplated to use glass spindle display indicia and to position a light beneath them, whereby refractive principles can be utilized to advantage, the rays being subject to a double refraction once by operation of the glass spindle display indicia and again by the walls of the housings 45.

According to the subsequent disclosure contained herein, and as fully described in my application for patent Ser. No. 216,361, the display elements 12 may comprise various shapes and modifications. The preferred form, however, as more clearly shown in Fig. 9 comprises a strip of reflecting material which is twisted so as to present continuously moving reflecting surfaces upon being rotated. A display member of this type is adapted to reflect light in all directions as it rotates, and consequently a light image reflected therefrom may be visible at acute angles. In many instances it may be desirable to taper the elements 12 as shown in Fig. 8. The strip may be of any suitable reflecting material, and in the present instance a display member formed from metal foil has proven most efficient. On the other hand a colored member may be used and it has been found that members having their opposite sides differently colored form a particularly attractive display.

As shown in Figs. 9 to 14, the rotatable display elements comprising spirally wound strips of reflecting material may be provided with any desired number of fins. Figs. 9, 10, and 11 show members comprising a strip which is twisted about its longitudinal axis to produce a spiral having but two fins. Fig. 12 shows a display member having four fins extending substantially at right angles from each other, and Fig. 13 shows a display member having three substantially equiangular fins. Each of these members is desirable for producing different effects or light patterns to be viewed by an observer. The use of these several types of display elements may be made according to the type of light pattern it is desired to obtain. The two-fin members as shown in Figs. 9, 10, and 11 produce a multiple unit sparkling or scintillating effect that includes a movement of the units along the length of the display member. In contrast, a four-fin member as shown in Fig. 12 produces more of a flaming effect having substantially no motion along the length of the member. On the other hand, the three-fin member as shown in Fig. 13 produces an effect substantially midway between that produced by the two-fin and the four-fin members. In other words, while producing a combined sparkling and flaming effect, there is also a slight movement of the light effect along the length of the reflector.

It has been discovered that if these display elements are formed in a predetermined manner they produce a light pattern that is considerably

more attractive than if they have other formations. This is particularly true with the two-fin display elements, and accordingly the member illustrated in Fig. 9 is shown to be formed in this manner. This desirable effect is obtained by twisting the strip so that each turn of 180° forms a reflector surface that is substantially square when viewed from the side of the strip. In other words the edge of each reflector surface will substantially coincide with the sides of a square A as shown in broken lines and the extreme opposite points of each reflector surface will lie in the sides of a square B midway between the corners thereof. The light pattern produced by this formation comprises a series of individual units or blobs of light which produce the maximum illumination and appear to be completely separated from each other.

A modification of the rotatable display element which has proven most desirable is shown in Fig. 10. This member is formed in a manner to provide a plurality of light reflecting surfaces so as to collect and reflect light from many angles. Furthermore the multiple reflecting surfaces break the light up into a plurality of units so as to give the effect of diffusion. This type of reflecting surface is more successful in producing a pattern or design of light rays and thereby disguising the physical formation of the display member. In addition, due to the fact that the reflecting surfaces lie in many planes at many different angles to each other, some of the light rays will be reflected at acute angles and consequently the light pattern will be visible even though an observer is located at one side of the sign. The undulating or deformed reflecting surface may be provided by forming the surface into a series of corrugations or ridges.

If a metal foil is used, as pointed out hereinabove, it may simply be crumpled and then more or less smoothed out so as to present a wrinkled surface. Another manner of forming a multiple reflector surface as shown in Fig. 11 is by cutting the edges of the fins as at 50 and bending the segments 51 between the slits 50 at angles with respect to each other or into angular segments. Other methods of obtaining a similar effect as above described may be used, such as forming convex or concave reflecting surfaces on the fins or by making indentations therein or in any other manner which will provide a display member having a plurality of reflecting surfaces which are arranged to reflect light from different angles. The preferred form, however, both from the standpoint of the light effect obtained, the ease of manufacture, and durability, is to corrugate the strip as described above. The modifications of this type of display member which are shown in Figs. 12, 13, and 14 may be arranged similar to the modifications just described and shown in Figs. 9, 10, and 11. That is, the fins of these members may have smooth surfaces, or the surfaces may be deformed so as to break up the light reflected therefrom into a plurality of units.

Another type of display element which may be incorporated in the present invention comprises but a single fin extending from one side of the axis thereof and is shown in Fig. 9. This single fin may be perfectly smooth, but preferably it is corrugated or otherwise deformed so as to break up the reflected light into a plurality of units. The single fin display element has many specific uses wherein the result produced thereby may be more attractive and successful than that

of the hereinbefore described display elements. For instance, a bank of single fin display elements may be used to produce a scintillating effect that appears to have a plurality of motions in different directions. On the other hand, due to the fact that the single fin may be of comparatively narrow width, a display element of this type may be used most successfully in combination with a narrow border panel surrounding or adjacent to the main portion of the sign.

Many different effects may be produced by the use of the various types of display elements above described and in the manner in which they are employed and/or driven. In constructing a sign according to the present invention, the type of display element to be incorporated therein may be chosen according to the type of matter to be advertised, the location of the sign with respect to its surroundings, and the location of the sign with respect to the observers.

Although certain specific embodiments of the present invention have been shown and described, many modifications thereof are possible, and the present disclosure should be construed only in an illustrative sense. The present invention, therefore, is not to be restricted except insofar as is necessitated by the prior art and by the spirit of the appended claims.

I claim:

1. A display sign comprising a support, display insignia mounted thereon, said insignia being composed of a plurality of rotatable elements provided with driving discs, and means to frictionally drive said driving discs, said driving discs being in edge engagement with said friction driving means.

2. A display sign comprising a support, display insignia mounted thereon, said insignia being composed of a plurality of rotatable elements, and means for resiliently maintaining said insignia in frictional engagement with a driving means.

3. A display sign comprising a support, display insignia mounted thereon in generally fixed position, said insignia being composed of a plurality of rotatable elements angularly positioned with respect to a driving surface and maintained in frictional engagement therewith, and means for imparting motion to said driving surface.

4. A display sign comprising in combination at least one symbol, said symbol comprising a plurality of rotating elements, reflecting means carried by said rotating elements that cooperate one with the other to define the symbol, friction means for imparting rotation to said elements, and a source of power for driving said friction means, whereby a scintillating effect is produced by the elements.

5. In a display sign, in combination, a support, display insignia mounted thereon, said insignia being composed of a plurality of rotatable elements, each of said elements comprising a shaft carrying a driving member and supporting a reflecting medium, said driving members being in edge engagement with a friction means, and a source of power for driving said friction means.

6. In a display sign, in combination, a support, display insignia mounted thereon, said insignia being composed of a plurality of rotatable elements, each of said elements comprising a shaft carrying a driving member and supporting a reflecting medium, said reflecting medium having plural surfaces whereby to reflect light rays in a plurality of directions, said driving members being in edge engagement with a friction means,

and a source of power for driving said friction means.

7. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis whereby to reflect light rays in a plurality of directions, said driving members being in edge engagement with a friction means, and a source of power for driving said friction means.

8. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis, said material being arranged so that each twist of 180° forms a substantially square reflecting face, whereby to reflect light rays so as to produce the appearance of individual spots of light, friction means for rotating said driving members, and a source of power for driving said friction means.

9. In a display sign, in combination, a support, a plurality of rotatable elements, each of said elements comprising a shaft carrying a driving member and supporting a reflecting medium, said reflecting medium comprising material twisted about its longitudinal axis and having plural surfaces, whereby to reflect light rays in a plurality of directions, said driving members being in edge engagement with a friction means, and a source of power for driving said friction means.

10. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis and having angularly formed surfaces, whereby to reflect light rays in a plurality of directions, friction means for rotating said driving members, and a source of power for driving said friction means.

11. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis and having corrugated surfaces, whereby to reflect light rays in a plurality of directions, friction means for rotating said driving members, and a source of power for driving said friction means.

12. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis whereby to reflect light rays in a plurality of directions, friction means for rotating said driving members, said driving members being resiliently maintained in frictional engagement with said friction means, and a source of power for driving said friction means.

13. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis so as to reflect light rays in a plurality of directions, a belt for frictionally engaging the driving members carried by said rotatable elements, and a source of power for driving said belt. 5
14. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis so as to reflect light rays in a plurality of directions, a roller for frictionally engaging said driving members, and a source of power for driving said roller. 10
15. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis so as to reflect light rays in a plurality of directions, a disc for frictionally engaging said driving members, and a source of power for driving said disc. 15
16. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis so as to reflect light rays in a plurality of directions, a frusto-conical disc for frictionally engaging said driving members, and a source of power for driving said disc. 20
17. In a display sign, in combination, a support, display insignia mounted thereon, said insignia being composed of a plurality of rotatable elements, each of said elements comprising a shaft carrying a driving member and supporting a reflecting medium, said reflecting medium comprising metal foil twisted about its longitudinal axis whereby to reflect light rays in a plurality of directions, means for illuminating the reflecting mediums, friction means for rotating said driving members, and a source of power for driving said friction means. 25
18. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis whereby to reflect light rays in a plurality of directions, means for illuminating the reflecting mediums, means for controlling the coloring of the illumination of said reflecting mediums, friction means for rotating said driving members, and a source of power for driving said friction means. 30
19. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis whereby to reflect light rays in a plurality of directions, friction means for rotating said driving members, and a source of power for driving said friction means. 35
20. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis and having angularly formed surfaces in the form of corrugations, said material being arranged so that each twist of 180° forms a substantially square reflecting face, whereby to reflect light rays in a plurality of directions, friction means for rotating said driving members, and a source of power for driving said friction means. 40
21. In a display sign, in combination, a support, display insignia mounted thereon, said insignia being composed of a plurality of rotatable elements, each of said elements comprising a shaft carrying a driving member and supporting a reflecting medium, said reflecting medium comprising material twisted about its longitudinal axis and having angularly formed surfaces in the form of corrugations, said material being arranged so that each twist of 180° forms a substantially square reflecting face, whereby to reflect light rays in a plurality of directions, means for illuminating the reflecting medium, means for controlling the color of the illumination of said reflecting medium, a belt for frictionally engaging the driving members carried by said rotatable elements, said driving members being resiliently maintained in frictional engagement with said belt and a source of power for driving said belt. 45
22. In display apparatus, in combination, a support, at least one rotatable display element supported by said support, said element comprising a reflecting medium composed of material twisted about its longitudinal axis, so that each twist of 180° forms a substantially square reflecting face, whereby to reflect light rays so as to produce the appearance of individual spots of light, and means for rotating said element. 50
23. In display apparatus, in combination, a support, at least one rotatable display element supported by said support, said element comprising a reflecting medium composed of metal foil twisted about its longitudinal axis and having plural surfaces, whereby to reflect light rays in a plurality of directions, and means for rotating said element. 55
24. In display apparatus, in combination, a support, at least one rotatable display element supported by said support, said element comprising a reflecting medium composed of material twisted about its longitudinal axis and having angularly formed surfaces, whereby to reflect light rays in a plurality of directions, and means for rotating said element. 60
25. In display apparatus, in combination, a support, at least one rotatable display element supported by said support, said element comprising a reflecting medium composed of material twisted about its longitudinal axis and having 65

corrugated surfaces, whereby to reflect light rays in a plurality of directions, and means for rotating said element.

26. In display apparatus, in combination, a support, at least one rotatable display element supported by said support, said element comprising a reflecting medium composed of material twisted about its longitudinal axis and having plural surfaces, said material having a plurality of slits along its edges and the portions there-between being bent to form said plural surfaces, whereby to reflect light rays in a plurality of directions, and means for rotating said element.

27. In display apparatus, in combination, a support, at least one rotatable display element supported by said support, said element comprising a reflecting medium composed of material twisted about its longitudinal axis, so that each twist of 180° forms a substantially square reflecting face and is provided with plural surfaces, whereby to reflect light rays so as to produce the appearance of individual spots of light, and means for rotating said element.

28. In display apparatus, in combination, a support, at least one rotatable display element supported by said support, said element comprising a reflecting medium composed of metal foil twisted about its longitudinal axis and having plural surfaces, whereby to reflect light rays in a plurality of directions, means for illuminating said reflecting medium, and means for rotating said element.

29. In a display apparatus, in combination, a support, at least one rotatable display element supported by said support, said element comprising a reflecting medium composed of metal foil twisted about its longitudinal axis so that each

twist of 180° forms a substantially square reflecting face, whereby to reflect light rays so as to produce the appearance of individual spots of light, and means for rotating said element.

30. In a display apparatus, in combination, a support, at least one rotatable display element supported by said support, said element comprising a reflecting medium composed of metal foil twisted about its longitudinal axis and having corrugated surfaces, whereby to reflect light rays in a plurality of directions, and means for rotating said element.

31. In a display apparatus, in combination, a support, at least one rotatable display element supported by said support, said element comprising a reflecting medium composed of metal foil twisted about its longitudinal axis and having angularly formed surfaces, whereby to reflect light rays in a plurality of directions, and means for rotating said element.

32. In a display apparatus, in combination, a support, at least one rotatable display element mounted on said support, said element comprising a strip of reflecting material twisted about its longitudinal axis to present a plurality of reflecting surfaces, said strip having a variable width whereby to produce variable sized reflecting surfaces.

33. In a display apparatus, in combination, a support, at least one rotatable display element mounted on said support, said element comprising a strip of reflecting material twisted about its longitudinal axis to present a plurality of reflecting surfaces, said strip being tapered whereby to produce progressively enlarged reflecting surfaces.

GEORGE H. EVANS.
